UNITED STATES PATENT OFFICE.

GEORGE A. TINNERMAN, OF CLEVELAND, OHIO.

DESIGN FOR A GAS AND COAL RANGE.

40,638.

Specification for Design.

Patented Apr. 12, 1910.

Application filed January 3, 1910. Serial No. 537,099. Term of patent 7 years.

To all whom it may concern:

Be it known that I, GEORGE A. TINNERMAN, a citizen of the United States, residing at Cleveland, in the county of Cuyahoga and State of Ohio, have invented a new, original, and ornamental Design for Gas and Coal Ranges, of which the following is a specification, reference being had to the accompanying drawing, forming a part thereof.

The figure of the drawing is a perspective view of the gas and coal range embodying my new design.

I claim—

The ornamental design for a gas and coal range, as shown.

GEO. A. TINNERMAN.
